(57) **CLAIM**

The ornamental design for a display panel or portion thereof with graphical user interface, as shown and described.

DESCRIPTION

FIG. 1 is a front view of a display panel or portion thereof with graphical user interface showing our new design; and, FIG. 2 is a front view thereof, shown with environmental matter.

The dot-dash broken lines in FIG. 1 illustrate a display panel or portion thereof and form no part of the claimed design. The broken lines in FIG. 2 showing a display device illustrate environmental matter that forms no part of the claimed design.

The elements that include four short solid line segments and are positioned at each end of the diagonal solid line in FIGS. 1 and 2 illustrate a portion of a graphical user interface and are meant to form part of the claim.

The display panel may be a display screen or any other suitable display panel. The display panel may be used with an ultrasound probe.
